CLAIM

The ornamental design for the toaster, as shown and described.

DESCRIPTION

FIG. 1 is a front view of a toaster incorporating the design of the present invention;

FIG. 2 is a right side view of the toaster of FIG. 1;

FIG. 3 is a top view of the toaster of FIG. 1;

FIG. 4 is a left side view of the toaster of FIG. 1; and, FIG. 5 is a perspective view of the toaster of FIG. 1, showing the front, right side, and top surfaces of the toaster.

The rear view of the toaster is a mirror image of the front view.

The bottom of the toaster is unornamented and is not visible during normal use.
